ATTORNEY.

UNITED STATES PATENT OFFICE.

MICHAEL J. WILLIAMS, OF BUFFALO, NEW YORK.

HAIRPIN.

1,410,981.

Specification of Letters Patent. Patented Mar. 28, 1922.

Application filed May 25, 1921. Serial No. 472,480.

To all whom it may concern:

Be it known that I, MICHAEL J. WILLIAMS, a citizen of the United States, residing at Buffalo, county of Erie, and State of New 5 York, have invented a new and useful Improvement in Hairpins, of which the following is a specification.

This invention relates to hair pins.

More particularly the invention relates to 10 the type of pins such as is shown in the patent granted to me—No. 1226836. This type of pin embodies prongs which are turnable or flexible, relatively to each other, to define loops in which strands of the hair are 15 confined in place—the pin being prevented from falling out of the hair or disengaged therefrom.

Some of the objects of the present invention are: to produce a hair pin which embodies sinuous prongs which normally cross each other, the prongs being capable of flexing action so that upon the insertion of the pin in the hair and by imparting thereto a slight twist the prongs will reverse themselves and will in their changed relation define a loop for the hair which has passed between the prongs—the prongs impinging against each other by virtue of the inherent flexibility of the material from which the 25 pin is made; to produce a hair pin of the character set forth from a piece of flexible wire which is covered with a flexible covering such as celluloid. With these and other 30 objects in view the invention resides in the particular formation and functions of the parts hereinafter more fully described and 35 illustrated in the accompanying drawing, in which:

Figure 1 is a side elevation of the hair 40 pin of the present invention, and in which the prongs of the pin are shown in their normal relative positions.

Figure 2 is another elevation of the pin with the prongs as shown in Figure 1.

Figure 3 is a view similar to the view 45 shown in Figure 1 but showing the prongs reversed and as they would be were the pin applied.

Figure 4 is a view similar to Figure 2 with 50 the prongs as shown in Figure 3.

Figure 5 is a cross-sectional view taken on the line 5—5, Figure 1.

Figure 6 is a view of a part of a pin constructed in accordance with the present invention and showing a modified form of bight which is especially adapted for use in 55

conjunction with eye-glasses, because a suitable chain may be properly connected to the pin.

Referring now more particularly to the several views of the drawing for details, it will be manifest that, the pin of the present invention shown in Figures 1 to 5 inclusive, is bent and formed from a single element to define a bight 10 from which extend 60 prongs 11 and 12. The prongs 11 and 12 are substantially identical in formation as regards their sinuosity. Each prong is bent or convexed inwardly just below the bight 10, bent outwardly and slightly rebent inwardly and then outwardly, thus providing a relatively long curved part 13 which merges with a part 14 which is bent or curved and then rebent as at 15 to extend 65 into a substantially straight part 16 having a pointed end 17. The prongs are so formed on the bight 10 and have such relation to each other that the parts 15 of the prongs 70 cross each other twice. It may now be well to mention that the element from which the pin is formed possesses the desired degree of 75 flexibility; that the prongs in their normal relation as shown in Figures 1 and 2 have a tendency to keep slightly spaced so that strands of the hair may readily pass between them in the application of the pin to use. The pin is pushed into the hair the proper distance when it is twisted. The 80 twisting, and inasmuch as the prongs are in engagement with the hair, causes the prongs 90 to be reversed, that is to say, the prong 11 instead of lying or being disposed on one side of the other prong 12, is disposed on the opposite side of the said prong 12. Under 85 this relation of the prongs, they have a 95 tendency to impinge against each other due chiefly to the inherent flexibility of the element from which the pin is made, and due partly to the formation of the pin. Under 100 the reversed arrangement of the prongs a loop 18 is formed as shown in Figure 3 and in such loop the strands of the hair are confined. When it is desired to remove the pin it is only necessary to first exert a twisting 105 action at the bight 10 which again reverses the relation of the prongs to their normal 110 condition thus allowing the pin to be readily withdrawn.

The element from which the pin is formed like other pins of this character is covered or coated. Pins now on the market are enamelled or japanned. While this may be

done with the pin of the present invention it is one of the objects to cover the material such as a steel wire with a flexible covering such as celluloid 19, as shown in Figure 5.

5 As shown in Figure 6 the pin 20 has a bight 21 which is formed by crossing the prongs. The bight 21 is therefore in the form of a circle to which a chain or the like may be connected for the connection of the 10 pin 20 to eye-glasses. The pin 20 with the exception of the bight 21 will be made identically to the pin of the preferred form.

What is claimed is:

15 1. A hair pin bent and formed from an element possessing flexibility to provide prongs which cross each other twice normally slightly spaced throughout the major portions of their length and which are capable of being brought to a relation so as to 20 define a loop and in which relation the prongs impinge each other.

20 2. A hair pin bent and formed from an element possessing flexibility to provide sinuous prongs which cross each other twice normally slightly spaced throughout the 25

major portions of their lengths, and which are capable of being brought to a relation so as to define a loop, and in which relation the prongs impinge each other, the said prongs each having a comparatively straight 30 part below the lowest point at which they cross each other.

3. A hair pin bent and formed from a composite element possessing flexibility, to provide sinuous prongs having curved parts 35 which intersect each other twice in the normal relation of the prongs but spaced to permit the passage of strands of hair therebetween, the twisting of the pin when engaged in the hair causing a reversed relation of the said prongs in which the said curved parts impinge each other due to the 40 flexibility of the element and the formation of the pin.

45 In testimony whereof, I hereby affix my signature.

MICHAEL J. WILLIAMS.
